FREDERICK W. BECKER, OF NEW YORK, N. Y.

TUNING-PEG FOR STRINGED INSTRUMENTS.

1,223,554.

Specification of Letters Patent. Patented Apr. 24, 1917.

Application filed November 20, 1913. Serial No. 802,019.

To all whom it may concern:

Be it known that I, FREDERICK W. BECKER, a citizen of the United States, and a resident of New York city, in the county of New York and State of New York, have invented certain new and useful Improvements in Tuning-Pegs for Stringed Instruments, of which the following is a specification.

This invention relates to tuning pegs for stringed instruments, particularly pegs of the type wherein frictional means is provided for holding the peg independent of the friction of the latter within its socket.

Among the objects of this invention may be mentioned the provision of a peg of this character which is strong and durable and gives uniform friction, removes all strain from the walls of the sound box, and from general outward appearance, does not differ materially from the usual peg hitherto used.

Further objects and advantages will more fully appear from the detailed description and the features of novelty consisting in the novel construction and combination of parts will be particularly pointed out in the claims.

In the drawing illustrating this invention, Figure 1 is a plan view and Fig. 2 is a side view of a peg box of a violin with my improved pegs applied thereto.

Fig. 3 is a section taken on line 3—3 of Fig. 2.

Fig. 4 is a sectional view of the key and bushing detached from the peg box, the section being taken at right angles to the section in Fig. 3.

Fig. 5 is a section taken along lines 5—5 of Fig. 3.

Fig. 6 is a detail plan view partly in section, and Fig. 7 is an end view of the stem portion of the peg.

Fig. 8 is a cross sectional detail view illustrating a modification.

Fig. 9 is a perspective view of the bushing illustrating the roughening.

Referring in detail to the drawing, the peg box 10, having the side walls 11 and 12, is provided with the usual apertures in which I insert respectively bushings 13 and 14. These bushings may be made of wood or some suitable composition and are held within the apertures either by their own friction or by some suitable adhesive. The peg proper consists of a stem 15 mounted loosely within the bushings and provided

at a suitable point intermediate its ends with a shoulder or collar 16 engaging the interior end of the bushing 13 and is formed at its outer end with a flattened portion 17 and a threaded extremity 18 of reduced diameter. Upon this flattened portion is loosely mounted a finger piece 19 which is frictionally held against the outer end of the bushing 13 by a thumb nut 20 screwed upon the threaded portion 18 of the stem. It will thus be seen that when the thumb nut is tightened, the stem is clamped against the ends of the bushing 13 and frictionally held thereby.

To secure a uniform friction at all times which can be adjusted to any desired degree without causing any binding action, I form the outer end of the bushing 13 with a circumferential enlargement 21 which is slightly dished at its side face, forming an annular frictional surface 22. The inner end of the finger piece 19 is also formed with a corresponding enlargement 23 and a slightly dished side face to present an annular frictional surface 24, corresponding to the surface 22. Preferably, a metallic washer 25 is inserted between the annular frictional surfaces to further reduce any possible binding action and to insure uniform friction at all times.

To increase the strength of the finger piece in its engagement with the flattened portion 17 of the peg, I preferably insert an angular washer 26 within the dished portion of the side face of the finger piece. This washer is formed with an angular aperture 27 corresponding to the section of the flattened portion 17. It will be noted that the long side of the opening in the finger piece extends transversely to the main body of the finger piece. This secures greater strength and avoids the tendency of the finger piece to crack which may occur when the long side of the aperture is positioned along the length of the flat body portion.

To further secure uniformity of the frictional resistance and also to protect the contacting surfaces, a washer 28 may be positioned between the collar 16 and the interior end of the bushing 13 and a washer 29 may likewise be located between the thumb nut 20 and the adjacent end of the finger piece. The metal washers prevent binding between the contiguous surfaces of the parts. The thumb nut is preferably formed with a me- 110

talic bushing 30 engaging the threaded portion 18 of the stem.

In the modified form illustrated in Fig. 8, the bushing 13^a is made shorter and does not quite reach the interior of the wall of the peg box. The shoulder 16 of the stem 15 engages a slightly dished washer 28^a the edge of which engages the interior of the wall of the peg box. The periphery of the bushing 13 may be roughened if desired as appears in Fig. 9 so as to more firmly engage the surface of the socket or aperture in the wall. Otherwise the construction is similar to that of the first form described.

15 It will thus be seen that I have provided a peg in which the friction is entirely independent both of the socket and of the walls of the peg box without adding any external parts to change the general appearance 20 of the peg constructed on the usual plan hitherto employed. The friction is entirely confined to the ends of the bushings and by reason of the flat annular frictional surfaces having considerable diameter as compared 25 with the diameter of the stem, not only is uniform friction assured at all times and in all adjustments, but also it will not be necessary to screw the thumb nut very tightly to secure the requisite amount of frictional 30 moment. The various parts are strong and durable and can also be readily replaced.

Having thus described my invention, I claim as new and desire to secure by Letters Patent:

35 1. A tuning peg for stringed instruments comprising a bushing adapted to be attached within an aperture in the wall of a peg box, a stem extending loosely through the bushing and adapted to have a string attached thereto, said stem being provided with a flattened shank and provided also with a collar engaging the inner end of the bushing, a finger piece for turning the stem mounted upon the shank and movable longitudinally 40 upon the shank and movable longitudinally upon the shank and movable longitudinally 45 thereon and adapted to engage the outer end of the bushing, and a thumb nut threaded upon the end of the shank to clamp the finger piece against the bushing, thereby holding the stem from rotation, the central portion of the adjacent ends of the finger piece and bushing being dished for the purpose set forth.

2. A tuning peg for stringed instruments comprising a bushing adapted to be attached 55 within an aperture in the wall of a peg box, a stem extending loosely through the bushing and adapted to have a string attached thereto, said stem being provided with a flattened shank and provided also with a collar engaging the inner end of the bushing, a finger piece for turning the stem mounted 60 upon the shank and movable longitudinally thereon and adapted to engage the outer end of the bushing, one of the engaging surfaces 65 being annular in form to produce a uniform

friction, and a thumb nut threaded upon the end of the shank to clamp the finger piece against the bushing, thereby holding the stem from rotation.

3. A tuning peg for stringed instruments 70 comprising a bushing adapted to be attached within an aperture in the wall of a peg box, a stem extending loosely through the bushing and adapted to have a string attached thereto, said stem being provided with a flattened shank and provided also with a collar engaging the inner end of the bushing, a finger piece for turning the stem mounted upon the shank and movable longitudinally thereon and adapted to engage 80 the outer end of the bushing, the engaging sides of the finger piece and bushing being enlarged to present a friction surface of considerable diameter, one of the friction surfaces being in the form of an annular 85 ring, and a thumb nut threaded upon the end of the shank to bring the friction surfaces into engagement and thereby hold the stem from rotation.

4. A tuning peg for stringed instruments 90 comprising a bushing adapted to be attached within an aperture in the wall of a peg box, a stem extending loosely through the bushing and adapted to have a string attached thereto, said stem being provided with a flattened shank and provided also with a collar engaging the inner end of the bushing, a finger piece loosely mounted upon the shank adapted to engage the outer end 95 of the bushing, the engaging ends of the finger piece and bushing being enlarged to a considerable diameter, the central portion of the engaging ends being dished whereby annular frictional surfaces disposed in planes 100 perpendicular to the axis of the stem are 105 formed, and a thumb nut threaded upon the end of the shank to bring the frictional surfaces into engagement.

5. A tuning peg for stringed instruments 110 comprising a bushing adapted to be attached within an aperture in the wall of a peg box, a stem extending loosely through the bushing and adapted to have a string attached thereto, said stem being provided with a flattened shank and provided also with a 115 collar engaging the inner end of the bushing, a finger piece for turning the stem mounted upon the shank and movable longitudinally thereon and adapted to engage 120 the outer end of the bushing, the engaging ends of the finger piece and bushing being enlarged to a considerable diameter, the central portion of the engaging ends being dished whereby annular frictional surfaces 125 disposed in planes perpendicular to the axis of the stem are formed, a washer of different material separating the friction surfaces, and a thumb nut threaded upon the end of the shank to bring the frictional surfaces 130 into engagement.

6. A tuning peg for stringed instruments comprising a stem extending loosely through the wall of a peg box and provided with a flattened portion, and a reduced threaded portion extending therefrom, a finger piece mounted upon the flattened portion and provided at its inner end with an annular friction surface of comparatively narrow width, a washer having an aperture corresponding to the flattened portion of the stem sunk in the interior end of the finger piece within the annular friction surface, and means engaging the threaded portion of the stem for clamping the friction surface of the finger piece against a portion stationary with the wall of the peg box.
7. A tuning peg for stringed instruments comprising a stem extending loosely through the wall of a peg box and provided with a flattened portion, and a reduced threaded portion extending therefrom, a finger piece mounted upon the flattened portion, the aperture in the finger piece through which said flattened portion passes having its long side extending transversely of the finger portion, the finger piece being also provided at its inner end with an annular friction surface of enlarged diameter but of narrow width, a washer having an aperture corresponding to the flattened portion of the stem sunk in the interior end of the finger piece within the friction surface, and means for clamping the friction surface of the finger piece against a portion stationary with the wall of the peg box.
8. A tuning peg for stringed instruments comprising a pair of bushings adapted to be attached within apertures in the walls of the peg box, a stem extending loosely through the bushing and adapted to have a string attached thereto, said stem being provided with a flattened shank and an elongated threaded portion extending therefrom and also with a projection engaging the inner end of one of the bushings, a finger piece removably mounted upon the shank for turning the stem and adapted to engage the outer end of the adjacent bushing, the contiguous portions of the finger piece and bushing being enlarged and formed with annular friction surfaces, the portion at the interior of the friction surfaces being dished to prevent contact of the same, a metallic washer between the friction surfaces, and a thumb nut threaded upon the end of the threaded portion of the stem adjacent to the finger piece

and adapted to force the friction surfaces into frictional engagement.

9. A tuning peg for stringed instruments comprising a pair of bushings adapted to be attached within apertures in the walls of the peg box, a stem extending loosely through the bushing and adapted to have a string attached thereto, said stem being provided with a flattened shank and a reduced threaded portion extending therefrom and also with a projection engaging the inner end of one of the bushings, a finger piece for turning the stem removably mounted upon the shank and yieldable longitudinally thereof and adapted to engage the outer end of the adjacent bushing, the contiguous portions of the finger piece and bushing being enlarged and formed with annular friction surfaces, the portion at the interior of the annular friction surfaces being dished to prevent contact of the same, a metallic washer between the friction surfaces, a thumb nut formed with a metallic bushing threaded upon the end of the threaded portion of the stem adjacent to the finger piece and adapted to force the friction surfaces into engagement, and washers between the projection on the shank and the inner end of the adjacent bushing and between the thumb nut and the adjacent end of the finger piece.

10. A tuning peg for stringed instruments comprising a bushing adapted to be attached within an aperture in the wall of a peg box, a stem extending loosely through the bushing and adapted to have a string attached thereto, said stem being provided with a flattened shank and provided also with a collar disposed within the peg box and serving as an abutment, a finger piece for turning the stem mounted upon the shank and movable longitudinally therein and adapted to engage the outer end of the bushing, one of the engaging surfaces being annular in form to produce a uniform friction, and a thumb nut threaded upon the end of the shank to clamp the finger piece against the bushing, thereby holding the stem from rotation.

Signed at New York city, in the county of New York and State of New York, this 17th day of September, A. D. 1913.

FREDERICK W. BECKER.
